UNITED STATES PATENT OFFICE.

FRED ASHWORTH, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

THREAD WAXING AND GUIDING DEVICE.

1,322,746.

Specification of Letters Patent. Patented Nov. 25, 1919.

Application filed February 8, 1917. Serial No. 147,411.

To all whom it may concern:

Be it known that I, FRED ASHWORTH, a citizen of the United States, residing at Beverly, in the county of Essex and State of Massachusetts, have invented certain new and useful Improvements in Thread Waxing and Guiding Devices; and I do hereby declare the following to be a full, clear, and exact description of the invention, such as will enable others skilled in the art to which it appertains to make and use the same.

This invention relates to thread waxing and guiding devices adapted to prepare thread for use in wax thread sewing machines.

The primary object of the present invention is to provide improved thread waxing and guiding devices by which a thread may be properly waxed and the wax on the thread held at the proper temperature after the thread leaves the waxing device.

With this and other objects in view, the invention consists in the improved thread waxing and guiding devices hereinafter described and particularly set forth in the claims.

The various features of the invention are illustrated in the accompanying drawings, in which Figure 1 is a view in side elevation partly in section of a bobbin winder and wax pot embodying the preferred form of the invention; Fig. 2 is a plan view of the improved wax pot; Fig. 3 is a detail view in side elevation of the wax pot heating member; Fig. 4 is a detail sectional view of the thread guiding device for the wax pot heating member; Fig. 5 is a detail sectional view taken on the line 5—5 of Fig. 1 illustrating the mounting of the bobbin winder thread truck upon its heating member; and Fig. 6 is a detail sectional view taken on the line 6—6 of Fig. 1 illustrating the mounting of the bobbin winder thread heating member upon its attaching bracket.

The thread waxing device illustrated in the drawings comprises a bracket 10 having a vertical portion provided with two slots 12 by which it is attached to the machine frame, and having a horizontal portion 13 which acts as a cover for the wax pot. A pair of ears 14 is formed at opposite sides of the cover 13, and between these ears is

removably mounted a pair of thumb screws 16 which are pivoted to the upper rim of 55 the wax pot 18. The wax pot consists of a metal container enlarged at the top to form a spout 20 which projects beyond the edge of the cover 13 to permit wax to be placed in the pot. 22 is a heating member provided 60 with four radiating wings extending from a central tubular portion 24. A pair of lugs 26 (Fig. 3) is formed on the lower face of the cover 13 and complementary lugs 28 are formed on two of the radiating wings of 65 the heating member 22 and are attached to the lugs 26 by means of screws 30. The tubular portion 24 of the heating member extends through the cover 13 and projects above its upper surface. An electrical re- 70 sistance heating unit 32 is received in the tubular portion and is connected with a pair of electrical conductors 34. The electrical conductors are inclosed in a conduit, which has a connector 36 on its lower end 75 which is adapted to fit over the tubular portion 24 where it may be clamped to lock the heating unit in the heating member.

The waxing device illustrated in the drawings is designed to wax the needle thread 80 of a sewing machine and also a bobbin thread. Each thread passes through a thread opening 38 in the cover 13 down along one side of a wing of the heating member, through a thread passage 40 in the 85 wing, up along the opposite side of the wing, and out through a wax stripper 42. Each thread passage 40 consists of a porcelain eyelet which fits into a socket 44 formed at the bottom of a wing, and is held in position by means of a clamping plate 46 secured to the bottom of the heating member by means of a screw 48. The wax stripper 42 is the well-known form of stripper which is shown and described in the patent to Ash- 95 worth No. 1,015,772, dated January 30, 1912. The stripper is threaded into the cover plate of the support and locked in position by means of a screw 50.

After the bobbin thread passes out through 100 the wax stripper it runs over a thread truck 52 mounted upon the connector 36 that is attached to the tubular portion 24. In the mechanism illustrated in the drawings the bobbin thread is wound upon a bobbin 54 105 which is secured by means of a thumb nut

58 upon the winding shaft 56 of a bobbin winding mechanism of well known construction. The winding shaft 56 is journaled in a bracket 60 and is provided with 5 a pulley 62 driven in the usual manner from the driving pulley of the sewing machine.

To keep the waxed thread in proper condition to be wound on the bobbin, a heating member 68 is provided. The heating member 68 consists of a metal tube in which is mounted an electrical resistance heating unit 70 connected to electrical conductors 72. The conductors 72 are inclosed in a conduit 74 which has a connector 76 at its lower end 10 constructed to be clamped over the end of the heating member 68. The heating member is supported upon a bracket 78 which is attached to the frame 60 and which is provided with an upwardly projecting thimble 80 on 15 which is clamped a sleeve 82 projecting from the side of the heating member 68 (see Fig. 6). The thimble 80 is directly in line with the bobbin 54 and the thread passes through the thimble in going to the bobbin. Below 20 and in line with the thimble 80 a downwardly projecting thimble 84 is formed on the lower end of the heating member 68. A bracket 86 is adjustably mounted on the thimble 84 and carries a thread truck 88 25 which is arranged to guide the thread along the axis of the thimble 84 (Fig. 5). The thread truck 88 is adjustable about the axis of the thread and may be set in any desired plane. By this construction the 30 thread trucks 52 and 88 may be adjusted on the tubular member 24 and thimble 84, respectively, so that the thread will be held in substantially one plane while it is passing from the thread stripper to the bobbin. The 35 thread truck 52 is heated by the heating unit 32 and the thread truck 88 is heated by the heating unit 70 so that the wax will not be allowed to harden before it gets to the bobbin. Also, the heating member 68 acts 40 to heat the thread as it passes through the thimbles 80 and 84, and keeps the thread hot until it reaches the bobbin 54. Heat is transmitted through the bracket 78 to the 45 frame 60 which tends to heat the shaft 56 and thus heat the bobbin 54. The adjustment of the heating member 68 upon the bracket 78 also allows it to be placed in position to get the greatest heat for the thread and be out of the way of the bobbin winding mechanism. The adjustment of the 50 heating member, however, does not affect the position of the thread truck 88.

The preferred form of the invention having been thus described, what is claimed is:

60 1. Thread waxing and guiding devices for sewing machines having, in combination, a

support, a wax pot attached to the support, a wax heating member secured to the lower face of the support and projecting into the wax pot, said member having a tubular portion projecting above the upper surface of the support, an electrical heating device in said tubular portion, a thread guiding device and thread stripper on the support, and a thread guide mounted on said tubular portion of the heating member above the thread stripper. 65

2. Thread waxing and guiding devices for sewing machines, having, in combination, a wax pot, a heating member projecting downwardly into the wax pot and provided with a radiating wing, an electrical heating device in said heating member, and means for guiding the thread downwardly through the pot on one side of said wing and upwardly 70 through the pot on the opposite side of said wing. 75

3. Thread waxing and guiding devices for sewing machines having, in combination, a wax pot, a heating member projecting downwardly into said pot and being provided with a radiating wing, and means for guiding a thread through said pot including an eyelet at the lower end of said wing to guide the thread from one side of the wing 80 to the other. 85

4. Thread waxing and guiding devices for sewing machines having, in combination, a wax pot, means for guiding the thread through said pot, a guide for the thread 95 after leaving the pot, a heating member having a passage for the thread after leaving said guide, means for heating said member, and a second thread guide on said member adjustable about the axis of said passage. 100

5. Thread waxing and guiding devices for sewing machines having, in combination, a wax pot, means for guiding the thread through said pot, a guide for the thread after leaving the pot, a heating member having a passage for the thread after leaving 105 said pot, said member being adjustable about the axis of said passage, and means for heating said member.

6. Thread waxing and guiding devices for 110 sewing machines having, in combination, a wax pot, means for guiding the thread through said pot, a guide for the thread after leaving the pot, a heating member having a passage for the thread after leaving 115 said guide said member being adjustable about the axis of the thread, a thread guide on said member adjustable about the axis of said passage, and means for heating said member.

FRED ASHWORTH.
